UNITED STATES PATENT OFFICE.

THOMAS F. COTE, OF MONTREAL, QUEBEC, CANADA.

FUSE PLUG.

Application filed April 26, 1921, Serial No. 464,529. Renewed May 10, 1924.

To all whom it may concern:

Be it known that I, THOMAS F. COTE, a subject of the King of Great Britain, residing at Montreal, in the Province of Quebec and Dominion of Canada, have invented certain new and useful Improvements in Fuse Plugs; and I do hereby declare the following to be a full, clear, and exact description of the invention, such as will enable others skilled in the art to which it 10 pertains to make and use the same.

This invention relates to new and useful improvements in fuse plugs of the character set forth in my Patent No. 1,424,714 and 15 has for its primary object the provision of means for closing the ends of the insulating sleeve which permits easy and quick removal of a burnt or destroyed fuse and the replacement of another in lieu thereof and also establishes an efficient electrical connection 20 between the fuse contact and the ferrule.

Another object of this invention is the provision of grooves arranged in the closing means of the sleeve for the purpose of 25 permitting the gradual escape of fumes or gases from the body to the atmosphere caused by the burning or fusing of the fuse and said grooves preventing the direct escape of flame from the body to the atmosphere, consequently reducing fire.

A further object of this invention is the provision of means for indicating when the fuse is destroyed and also adapted to indicate the amperage of the fuse and further to 35 retard the entrance of foreign matter to the interior of the body.

A still further object of this invention is the provision of a fuse plug of the above stated character, which will be simple, durable, and efficient, and which may be manufactured and sold at a comparatively low cost.

With these and other objects in view as will become more apparent as the description 40 proceeds, the invention consists in certain novel features of construction, combination, and arrangement of parts as will be hereinafter more fully described and claimed.

For a complete understanding of my invention, reference is to be had to the following description and accompanying drawings in which:—

Figure 1 is a vertical sectional view illustrating a fuse plug constructed in accordance 55 with my invention,

Figure 2 is a vertical sectional view illus-

trating the cover with the ferrule located therein,

Figure 3 is a perspective view illustrating the sleeve with the closure caps applied thereto,

Figure 4 is a perspective view illustrating a modified form of cap.

Referring in detail to the drawings, the numeral 1 indicates a body constructed from porcelain or any other material suitable for the purpose and is provided with a chamber 2 and one end of the body is closed by an end wall 3 provided with a centrally arranged opening 4 to receive a contact 5 that projects slightly beyond the outer face of the end wall as clearly shown in Figure 1. The contact 5 consists of a hollow body 6 that has its outer end closed and its inner end has formed integrally therewith a flange 7 adapted to seat against the inner face of the end wall 3. The other end of the body 1 is opened and closed by a removable cover 7' constructed from porcelain or any other material suitable for the purpose and said cover has seated therein a ferrule 8, the side walls of which have pressed therein screw threads 9 adapted to cooperate with screw threads 11 formed within the cover 7' and also adapted to cooperate with screw threads 12 formed on the body 1 to detachably secure the cover 7' to the body. The screw threaded wall of the ferrule 8 projects beyond the side wall of the cover 7' and overlies a portion of the body and is adapted to have threaded connection with the usual fuse socket (not shown). The cover 7' is provided with a centrally arranged vent opening 13 in its top wall and aligns with a vent opening 14' formed in the ferrule 8.

An insulating sleeve 14 is arranged within the chamber 2 and spaced from the wall thereof and has its ends closed by closure caps 15 of cup-shape and the side walls thereof are slightly flared outwardly as illustrated at 16 at their edges for facilitating the application of said caps to the ends of the sleeve 14. The caps have frictional contact with the sleeve and are adapted to secure the ends of a fuse 17 against the ends of the sleeve 14. The ends of the fuse 17 are bent angularly and overlie the ends of the sleeve and retained in engagement therewith by the closure caps and the major portion of the fuse extends diagonally through the sleeve. The sleeve is provided with a vent

opening 18 for the purpose of permitting fumes or gases within the interior of the sleeve to escape into the body on the burning or fusing of the fuse 17.

5 The lowermost cap 15 seats against the contact 5 while the uppermost cap seats against the ferrule 8, consequently forming an efficient electrical connection between the ends of the fuse and the contact 5 and the ferrule 8. The ferrule 8 is constructed from a suitable metal.

The closure caps 15 have a plurality of radially extending grooves 19 pressed in their outer faces and the grooves of one cap 15 establish communication between the vent 14' and the interior of the body. The caps 15 have pasted or otherwise secured thereto disks 20 bearing the amperage of the fuse and of a size substantially equal to the size 20 of the vent opening 14' and one of said disks, depending on which cap is disposed uppermost, is adapted to close said vent opening. The disks also close the inner ends 25 of the grooves 19, thus it will be noted that the grooves as well as the vent opening 14' are closed by said disk preventing the entrance of foreign matter into the chamber 2. The disks are constructed from paper or any other material which is readily destructible 30 by fire and the disks are pasted or otherwise secured onto the respective caps.

The destruction of the fuse 17 by an overcharge of electricity, causes the same to burn out and create a certain amount of flame and gases which escape into the chamber 2 whence they may expand into the interior of the contact 5 and also gradually escape from the chamber 2 by way of the grooves in the uppermost cap and the vent openings 40 14' and 13 respectively. The disk 20 being of a fragile material will quickly become destroyed or mutilated by the flame and gases as they escape from the chamber 2 and thereby indicate that the fuse has been destroyed without the necessity of removing the cover 7 and ferrule 8 from the body in order that the uppermost cap 15 may be removed from the sleeve in order to expose the fuse.

50 As shown in Figure 4 the disk 20 may be dispensed with and the amperage of the fuse may be stamped or otherwise applied directly to the caps.

The contact 5 being of hollow formation 55 allows the gases entering in the chamber 2 from the sleeve 14 to expand into the same whence said gases may gradually escape back into the chamber and thence out to the atmosphere by way of the vent openings 13 and 14' and the grooves in the uppermost cap. The body 6 of the contact 5 being of hollow formation also permits the flange 7 to be easily formed by simply bending or stamping a portion of the body laterally.

While I have shown and described the

preferred embodiment of my invention, it will be understood that minor changes in construction, combination and arrangement of parts may be made without departing from the spirit and scope of the invention 70 as claimed.

Having thus described my invention what I claim is:—

1. A fuse plug comprising a body, a ferrule for said body and having a vent, a contact for said body, a sleeve in said body and having an opening, a fuse in said sleeve, and caps closing the ends of the sleeve and securing the fuse to the sleeve and engaging the contact and the ferrule at the vent, said 80 caps having grooves and the grooves of one cap establishing communication between the vent and the interior of the body.

2. A fuse plug comprising a body, a ferrule for said body and having a vent, a contact for said body, a sleeve in said body and having an opening, a fuse in said sleeve, cup-shaped caps closing the ends of the sleeve and having frictional contact with the latter and securing the ends of the fuse to 90 the sleeve and engaging the ferrule and the contact, said caps having grooves and the grooves of one cap establishing communication between the interior of the body and the vent.

3. A fuse plug comprising a body, a ferrule for said body and having a vent, a cover carried by said ferrule and having a vent in alignment with the first named vent, a contact for said body, a sleeve in said body and having an opening, a fuse in said sleeve, caps closing the ends of the sleeve and having grooves therein, said caps engaging the ferrule and contact and the grooves of one cap establishing communication between the vents and the interior of the body.

4. A fuse plug comprising a body, a ferrule for said body and having a vent, a contact for said body, a sleeve in said body and having an opening, a fuse in said sleeve, caps closing the ends of the sleeve and engaging the ferrule and the contact, said caps having radially extending grooves opening outwardly of the peripheries of said caps 115 and having their inner ends relatively spaced, the grooves of one cap establishing communication between the interior of the body and the vent, and destructible means closing the vent and grooves.

5. A fuse plug comprising a body, a ferrule for said body and having a vent, a contact for said body, a sleeve in said body, a fuse in said sleeve, caps frictionally engaging said sleeve and engaging the ferrule and the contact, said sleeve having an opening, said caps having grooves with their inner ends relatively spaced and disposed under the vent to establish a communication between the latter and the interior of

the body, destructible disks bearing the amperage of the fuse secured to the caps and closing the inner ends of the grooves thereof and one of said disks closing the vent.

6. A fuse plug comprising a body, a ferrule for said body and having a vent, a contact carried by said body and having a hollow body portion, an integral flange formed on said body portion and engaging the body, a sleeve in said body, a fuse in said sleeve, caps closing said sleeve and one of said caps resting upon the flange and the other cap engaging the ferrule, said sleeve having an opening, said caps having grooves establishing communication between the body and the hollow body portion of the contact and the interior of the body and the vent, and destructible means closing the grooves of the caps and the vent.

7. A fuse plug comprising a shell having a vent, a vented fuse containing element in said shell with one end abutting the latter about the vent and provided with passages

to establish communication between the interior of the shell and the vent.

8. A fuse plug comprising a shell having a vent, a vented fuse containing element having closed ends located in said shell with one end engaging the latter about the vent and having grooves in said last named end to establish communication between the vent and the interior of the shell.

9. A fuse plug comprising a shell having a vent, a vented fuse containing element having closed ends located in said shell with one end engaging the latter about the vent and having grooves in said last named end to establish communication between the vent and the interior of the shell, and destructive means closing the grooves and adapted to bear the amperage of the fuse.

In testimony whereof I affix my signature in presence of two witnesses.

THOMAS F. COTE.
